UNITED STATES PATENT OFFICE.

CHARLES E. SCRIBNER, OF CHICAGO, ILLINOIS, ASSIGNOR TO THE WESTERN ELECTRIC COMPANY, OF SAME PLACE.

TELEPHONE-EXCHANGE SYSTEM.

SPECIFICATION forming part of Letters Patent No. 669,707, dated March 12, 1901.

(Application filed November 12, 1894. Serial No. 528,526. (No model.)

To all whom it may concern:

Be it known that I, CHARLES E. SCRIBNER, a citizen of the United States, residing at Chicago, in the county of Cook and State of Illinois, have invented a certain new and useful Improvement in Telephone-Exchange Systems, (Case No. 361,) of which the following is a full, clear, concise, and exact description, reference being had to the accompanying drawings, forming a part of this specification.

My invention relates to signaling appliances for telephone-exchange systems; and it consists in improved apparatus for automatically transmitting signals for connection and disconnection between substations and the central station or exchange.

The system of my invention comprises a source of signaling-current located at the exchange; a group of line-wires connected in common with the signaling-battery, each including a signaling-annunciator, the circuit of the signaling-battery through the line-wire and annunciator being normally closed at each substation; means for opening the circuit while the telephone at the substation is in use; a clearing-out annunciator adapted to be connected with two united lines and constructed to give a signal in response to the completion of the circuit at the substation, and a device for preventing the operation of the line-annunciator while a line is in use. The line-annunciator which I employ and which, together with the circuits appropriate to it, constitutes a feature of my invention, comprises an indicator, a line-magnet arranged to conceal the indicator when it is excited, and an auxiliary restoring-magnet adapted to cause the indicator to be concealed independently of the action of the line-magnet. The line-magnet of this annunciator is included in the corresponding line-circuit, and the auxiliary magnet, which I will designate the "restoring-magnet," is included in a normally open local circuit which is automatically closed at any spring-jack in the act of inserting a plug therein to connect with the line. The clearing-out annunciator is included in a branch of the signaling-battery to the conductor of the plug-circuit, so that while the circuit of the line with which con-

nection is made by means of the plugs is complete at the substation the clearing-out annunciator will display its signal.

In this system the annunciator of a line is retained in position to conceal its indicator as long as the telephonic apparatus at the substation is not in use, the circuit of the signaling-battery through the line-annunciator being then continuous. When the telephone is brought into use, the signaling-current is automatically interrupted at the substation, whereby the line-magnet of the line-annunciator is deprived of current and permits the annunciator-signal to be displayed. Connection is then made with the line by means of plugs in the usual way. The restoring-magnet of the annunciator is thereby excited and again conceals the indicator or target of the annunciator, while at the same time the clearing-out annunciator becomes connected in a branch of the line-circuit. When the connection is completed with the line called for—the "answering-line"—the local circuit through the restoring-magnet of the corresponding line-annunciator is closed, so that the operation of the line-annunciator of the answering-line when the telephone is brought into use to answer is prevented. Upon the completion of conversation and the replacement of the telephones upon their switch-hooks at the substations the signaling-circuit is again closed. The clearing-out annunciator in a branch between the line and the signaling-battery is thus excited and displays its signal, which is interpreted as a signal for disconnection.

My invention is illustrated in the accompanying drawings.

Figure 1 of the drawings is a diagram representing the general organization of the system as applied to a multiple switchboard of two sections, two substations being shown connected with the exchange. Fig. 2 is a side elevation of the line-annunciator. Fig. 3 is a similar elevation of the clearing-out annunciator which I employ.

The apparatus at the substation—for example, at substation A—comprises a telephone b and transmitter b' and a signal-bell b'' in separate branches from the line, an automatic telephone switch-hook b^3 being provided to

switch the line into connection with either the telephone or the signal-bell. The signal-bell b^2 may be of comparatively low resistance. The branch containing the telephone appliances should be of high resistance to continuous currents, a condenser b^4 being preferably included in the circuit through them. The substation apparatus is connected by means of line-wire 1 with the spring-jacks c and c' , 5 one upon each section d and d' of the multiple switchboard, and includes the line-coil e of an annunciator f upon the section d' . The line after passing through the annunciator-coil is grounded through a battery g , which 10 is common to all lines of the exchange. Each spring-jack comprises three contact-pieces—a thimble h and two normally-separated springs h' and h^2 . The thimble h is connected with the line conductor of the line, the spring 15 h' is grounded, and the spring h^2 is connected, through the restoring-coil e' of annunciator f , with the terminal of battery g .

The construction of annunciator f is shown in Fig. 2. It comprises a core upon which are 20 wound two helices e and e' , a shutter e^2 , which serves as an armature for the core, and a light shield or indicator e^3 , which is adapted to be acted upon by the shutter e^2 . The shutter e^2 is pivoted at its lower edge and a little to one 25 side of its center of gravity on trunnions e^4 in a bracket e^5 , forming part of the frame of the instrument. Before the shutter is hung the shield e^3 , being pivoted at its upper edge in an extension of the bracket. The shutter e^2 carries 30 a projection which is adapted to engage the shield e^3 near its pivotal point as the shutter falls outward and to throw the shield into a nearly horizontal position, whereby the face of the shutter e^2 is displayed. The shutter 35 may bear any suitable number or other target upon its face.

As long as current exists in either helix e or e' of the magnet the core is magnetized and attracts the shutter to it, permitting the 40 shield e^2 to hang freely. When both magnets are unexcited, the shutter falls forward and throws the shield into its horizontal position, as described.

The operator's appliances for switching 45 lines into connection with each other and for performing the various operations involved in this are of the usual character. The connecting-plugs, however, are adapted for use in the particular form of spring-jack here 50 employed. Each plug, as i , comprises an insulated tip i' and a shank i^2 . The tip is adapted to cross together the springs h' h^2 , while the shank makes connection with the thimble h . The shanks of the plugs i and i^3 , 55 which constitute a pair, are connected together by a conductor 2, which includes the switch-contacts of a pair of calling-keys k and k' , either of which when depressed is adapted to disconnect the corresponding plug 60 from the other plug and to connect it with the terminal of a generator l of signaling-current adapted to operate the signal-bell b^2 .

An operator's telephone set m is connected with the anvil of a listening-key n , by which the operator may bring her telephone into 70 connection with conductor 2 of the plug-circuit.

In a branch from conductor 2 of the plug-circuit, extending to the terminal of battery g , is included the clearing-out annunciator o . 75 This annunciator is represented in Fig. 3. It comprises an electromagnet p , a pivoted armature or shutter p' , and a shield p^2 . The shutter p' is pivoted at its lower edge, so as to fall outward when unattracted. The shield p^2 hangs in front of shutter p' , being pivoted near its upper edge. It carries a short projection beyond its pivotal point, engaging with a hook upon the shutter p' . When the shutter, being unattracted, falls outward, 80 shield p^2 hangs freely in its vertical position; but when the shutter is attracted the hook engages the projection of the shield and throws the latter into a horizontal position, disclosing the face of the shutter. 85

The operation of the system may now be traced with reference to Fig. 1. While the telephone at the substation rests on the switch-hook b^3 the circuit of battery g is completed through magnet e of annunciator f of 90 line 1 and signal-bell b^2 . Magnet e is thus excited, whereby the shutter of the annunciator is attracted and the face of the shutter is concealed. When the telephone is removed from the hook, as shown in the drawings, the flow 95 of the battery-current is interrupted by condenser b^4 . Magnet e is thus de-activated, shutter e^2 falls outward, and shield e^3 is raised and gives the signal of the annunciator. The attendant at section d' , where annunciator f is 100 located, seeing this signal, inserts plug i into the corresponding spring-jack c' , at the same time depressing her listening-key n to connect her telephone with the circuit. Circuit 105 from substation A is thus continued through the operator's telephone appliances m and she is placed in communication with the call-initiating subscriber. At the same time springs h' h^2 are crossed together, whereby the local 110 circuit of magnet e' is closed and the magnet, thus excited, retracts armature e^2 and effaces the signal. The annunciator o is now connected with the line through the medium of plug-circuit 2; but since the line-circuit is 115 open at station A the annunciator does not display its indication. The operator having tested line to station A' and found it free inserts plug i' into spring-jack c^3 of that line. The local circuit through the restoring-magnet of annunciator f' of that line is now closed. 120 The operator signals the subscriber at station A' by depressing calling-key k' , and the subscriber, having responded, removes the telephone from the switch-hook b^3 . The circuit 125 from battery g through magnet e to earth at 130 the substation is thus interrupted, but since the magnet e' is still excited the annunciator is not operated. When the subscribers have finished their conversation, either may re-

place his telephone *b* upon the switch-hook. The circuit from conductor 2 of the plug-circuit to earth at that substation is thereby completed. Current from battery *g* flows 5 through the magnet of clearing-out annunciator *o* and operates it, thereby instantly displaying the signal for disconnection. When the operator has removed the plugs from the spring-jacks, all the circuits are returned to 10 their normal condition.

Having thus described my invention, I claim as new and desire to secure by Letters Patent—

1. In combination, an indicator adapted 15 when released to display a signal, two electromagnets adapted to act independently upon said indicator to prevent its display, a normally-closed circuit containing one of said electromagnets and means for interrupting 20 the said circuit, and a normally-open circuit containing the other electromagnet and means for closing the same circuit, substantially as described.
2. In combination in an annunciator, a shutter adapted to fall to give a signal, two electromagnets acting independently upon the shutter to prevent its fall, a normally-closed telephone-circuit including one of said magnets and means for interrupting the said circuit, 30 and a normally-open local circuit containing the other magnet and means for closing said circuit, substantially as described.
3. The combination with a telephone-line, means for producing current in the line, and 35 a switch adapted to interrupt the current during the use of the telephone, of an annunciator and a target controlled thereby adapted to be displayed when the annunciator-magnet is inert, an auxiliary winding on the said magnet, a local circuit therethrough, and means 40 for closing the local circuit in making connection with the line, a clearing-out annunciator adapted to display a signal when excited, and means for bringing the clearing-out annunciator into connection with the line, 45 as described.
4. In combination with a normally-continuous telephone-line, an annunciator having an indicator and two electromagnets adapted to 50 act independently upon the indicator to prevent its display, one of said electromagnets being included together with a source of current in the telephone-line, a normally-open local circuit including the other magnet and 55 a source of current, and switch-contacts adapted to close the local circuit when connection is made with the line, substantially as described.
5. In combination with a normally-continuous 60 telephone-circuit extending from a substation to an exchange, a switch at the substation adapted to open the line during the use of the telephone, spring-jacks connected

with the line at the exchange, an annunciator having an indicator and two electromagnets each adapted to prevent the display of the indicator, one of the magnets being included together with a source of signaling-current in the telephone-line, a normally-open local circuit including the other magnet of the 65 annunciator, and switch-contacts adapted to close the local circuit at any spring-jack when connection is made therewith, substantially as described.

6. The combination with an electromagnet 75 of an armature-shutter pivoted at its lower edge and adapted to fall outward when unattracted, of a pivoted shield suspended before the shutter, an arm projecting beyond the pivotal point of the shield, and a projection upon the shutter adapted to engage the arm to throw the shield into a horizontal position, as described.

7. The combination with a telephone-circuit 85 extending from a substation to an exchange and closed at the substation through a circuit of high resistance, a switch at the substation adapted to close the line during the disuse of the telephone through a circuit of lower resistance, an annunciator having 90 two electromagnets adapted to act independently on its indicator to prevent the display thereof, one of said magnets being included together with a source of current in the telephone-circuit, and the other being included 95 with a source of current in a closed local circuit, a clearing-out annunciator adapted to give a signal when its magnet is excited temporarily included with a source of current in a branch between the sides of the telephone-circuit, and means for opening the local circuit when the clearing-out annunciator is disconnected, substantially as described.

8. The combination with an electromagnet and its armature, of a pivoted shield depending before the face of the armature and hiding the same, and a hook carried by the armature, adapted to engage said shield near its pivotal point, thereby causing the display of the target or face of the armature 105 when the armature is attracted, substantially as described.

9. The combination with an electromagnet and the armature thereof pivoted at its lower edge, of a shutter depending before the armature from its upper edge adjacent to the armature, an extension of the shutter above its pivotal point, and a hook carried by the armature engaging said extension, substantially as described.

In witness whereof I hereunto subscribe my name this 20th day of August, A. D. 1894.

CHARLES E. SCRIBNER.
